DESIGN FOR A FLUFFED YARN ANIMAL FIGURE

Victor J. Kritske and Jeanette M. Kritske,
Sheboygan, Wis., assignors of one-half to William H. Murphy, Chicago, Ill.

Application May 23, 1945, Serial No. 119,691

Term of patent 14 years

(Cl. D34—2)

To all whom it may concern:

Be it known that we, Victor J. Kritske and Jeanette M. Kritske, citizens of the United States, and residents of Sheboygan, in the county of Sheboygan and State of Wisconsin, have invented a new, original, and ornamental Design for a Fluffed Yarn Animal Figure, of which the following is a specification, reference being had to the accompanying drawing, forming a part thereof.

Fig. 1 is a front perspective view of a fluffed yarn animal figure showing our new design.

Fig. 2 is a rear perspective view of the fluffed yarn animal figure shown in Fig. 1 taken from the other side.

We claim:

The ornamental design for a fluffed yarn animal figure, substantially as shown and described.

VICTOR J. KRITSKE.
JEANETTE M. KRITSKE.
